UNITED STATES PATENT OFFICE.

CHARLES E. MOORE, OF NEW YORK, N. Y., ASSIGNOR, BY MESNE ASSIGNMENTS, TO ELEVATOR SUPPLY & REPAIR COMPANY, A CORPORATION OF ILLINOIS.

THRESHOLD-ILLUMINATOR.

1,164,301.

Specification of Letters Patent. Patented Dec. 14, 1915.

Application filed October 1, 1913. Serial No. 792,753.

To all whom it may concern:

Be it known that I, CHARLES E. MOORE, a citizen of the United States, and a resident of the city of New York, borough of 5 Manhattan, in the county and State of New York, have invented a new and Improved Threshold-Illuminator, of which the following is a full, clear, and exact description.

This invention relates to certain improvements in passenger conveyances such, for instance, as elevators in buildings, railway cars or the like, and the invention contemplates certain features of advantage in the nature of improvements over the invention 15 disclosed in Letters Patent of the United States, No. 885,942, issued to me on April 28, 1908.

Among the objects of the present invention is to improve the construction and operation of the illuminator casing whereby the same is adapted to occupy a minimum amount of room and has lighting facilities for the particular purposes of the invention superior to any device previously proposed and which also is more reliable.

Another object of this invention is to improve the means for controlling the time at which the light becomes effective with respect to the controlling mechanism of the 30 moving vehicle.

The invention also contemplates improved features of construction in various details hereinafter more fully set forth.

The foregoing and other objects of the 35 invention will hereinafter be more fully described and claimed and illustrated in the drawings forming a part of this specification in which like characters of reference indicate corresponding parts in all the views, 40 and in which—

Figure 1 is a vertical sectional view of the inside of a conventional form of elevator car, the view being taken on a plane parallel to the front of the car and looking 45 toward the doorway and controlling mechanism; Fig. 2 is an elevation indicating the relation of the lamp controlling switches to the car controller, the switches in this view being both closed as when the lamps are 50 burning; Fig. 3 is a view corresponding to Fig. 2, but with one of the switches open, such as when the controlling lever not shown in this view is in running position; Fig. 4 is a vertical sectional view of one of the 55 switches taken on the line 4—4 of Fig. 2;

Fig. 5 is a transverse section taken on the line 5—5 of Fig. 4; Fig. 6 is a diagram of the electric connections; Fig. 7 is a front elevation of the illuminator casing; Fig. 8 is a vertical section on the line 8—8 of Fig. 7; and Fig. 9 is a transverse section of the same on the line 9—9 of Fig. 8.

The several parts of the device may be made of any suitable materials, and the relative sizes and proportions, as well as the 60 general design of the mechanism, may be varied to a considerable extent without departing from the spirit of the invention hereinafter more fully set forth and specifically claimed.

While I show the invention applied to a passenger elevator, I wish it to be distinctly understood that it is also adaptable for use on electric railway cars or other forms of passenger vehicles, and hence while I may 70 for convenience of expression use the terms "elevator" or "elevator car," such terms are to be interpreted broadly enough to cover any device to which my invention may be applied and in other respects the terms of 75 the claims are to be given an interpretation as broad as the state of the art will warrant.

At 10 I show a car having a doorway 11 and a threshold 12. Said doorway may 80 be closed by a car door but since such door forms no part of the present invention the same is not shown. I show, however, at 13 an operating lever which is symbolic of any suitable hand operated controlling mechanism whereby the elevator conductor controls the operation or movements of the car or any of the parts associated therewith such for instance as the car door or shaft gate, in any well known or approved manner. Said lever 13 is connected to a shaft 14 journaled as usual beneath the floor of the car and the axis of said shaft constitutes the pivot around which the lever may swing in the arc of a circle in either direction from 90 the normal or stopped position shown in Fig. 1.

At 15 I show an illuminator casing of peculiar form located conveniently at either side of the doorway 11, and having an elongated vertically disposed opening facing the threshold of said door. This casing is equipped with a plurality of lamps 16 arranged one above the other and in parallel in the same circuit 17, the light from said 110

lamps being adapted to be thrown or flashed out from its elongated opening and across the threshold of the car and the landing at which the car is being stopped. The light being caused to flash out as above described serves a number of important purposes among which are, first, to indicate not only to the conductor but to the occupants of the car that the car is being stopped and therefore the conductor is assisted in bringing his car precisely to the landing; secondly, it serves as an indicator to the passengers entering or leaving the car that the car is at the landing and hence in position for transfer of passengers; and thirdly, the light is thrown or flashed just where it is needed to enable the passengers to pass the doorway in complete safety or without stumbling or groping.

20 In order to effect the foregoing advantages I find it essential or desirable for the light circuit 17 to be completed or broken at various times to suit it to the various types of cars which may be equipped therewith, the variety of types having reference to differences of speed and to the space intervals which must be observed between the time of movement of the operating lever to effect the stopping of the car and the time of actual stopping. More specifically, in the stopping of a high speed car the operating lever must be moved toward stopping position at a greater distance from the landing than in a slow speed car. It is therefore important or desirable that the switches or contacts which initiate the illumination shall be made operative nearer the final position of the operating lever than in the case of a slow speed car.

40 The circuit in this preferred form of the invention, therefore, includes a pair of switches or circuit breakers 18 and 19 arranged on opposite sides of the operating lever when in mid position and adjustable 45 toward or from said operating lever in accordance with the varying conditions above referred to. The location or adjustment of the switches, it will be understood, is independent of the extent of movement of the operating lever in either direction from its normal position. In other words, the operating lever is adapted to pass either of the switches when starting the car, and after the operating lever passes the switches on 50 movement to running position, there will be no cooperation between the operating lever and the switches or any part of the circuit until the operating lever is started back and approaches its mid position again.

60 The casing 15 is supported upon a pedestal 20 secured preferably upon the floor 21 of the car, though as to the particular means for securing the pedestal in place I do not wish to be limited. The means 65 shown, however, is reliable and satisfactory.

The casing is substantially rectangular in form and of considerable height in comparison with its cross sectional area. The pedestal 20 is hollow and the circuit wires are led upwardly therethrough and the circuit within the casing includes not only the lamps 16 but also preferably a key switch 22 whereby the lamps may be extinguished when the car is left standing for any length of time. The front of the casing consists of a removable plate 23, that portion of which is in front of the lamp comprises a series of transverse, parallel, downwardly inclined shutters or baffles 24 mounted in fixed position at the sides of said casing. As shown in Figs. 1 and 8, said baffles are so arranged as to concentrate the rays of light upon the threshold of the car and the landing, and they prevent, therefore, any blinding effect of the intense light from within the casing interfering with the expeditious transfer of the passengers. Said plate 23 is removably secured to the front of the casing by means of screws 25 whereby easy access may be had to the lamps when necessary for inspection or repair, and at the lower end of the casing is provided an openable cover 26 giving access to the key switch 22. The lamps 16 may be of any well known construction and each is seated in its own socket 16' shown as secured in the end of a reflector 27 having a concave rear wall for the purpose of intensifying the light effect. With the lamps in parallel, the apparatus is not disabled in the event of either of the lamps becoming broken or burned out.

The switch devices 18 and 19 are substantially alike in character and construction except that they are made rights and lefts for operation in pairs. A description of one of them, therefore, will be understood as being applicable to both. Each switch device in its preferred form comprises a casing 28 adjustably related to the path of movement of the controller and secured in any desired position with respect to distance from the normal position of the operating lever by any suitable means as, for instance, by clamping or binding screws 29 operating through the rear wall of the casing 28. The switch proper, indicated at 30 is pivoted on a stud 31 fixed to said rear wall, said switch being adapted to oscillate in a plane substantially parallel to the plane of movement of the operating lever. The switch 30 includes a main body portion having a pair of laterally divergent depending portions 32 and 32', and secured to said body or extending upwardly therefrom on the opposite side of the pivot 31 from said depending portions is a stem 33 which carries a peculiar bridge piece 34 insulated, however, from the stem and body by a spool-shaped insulating member 35. The members 34 and 35 are secured in place on the stem by means of a

screw 36 tapped into the upper end of the stem and a fiber washer 37 completes the insulation between the bridge member 34 and the stem. Circuit wires lead into the casing preferably from the rear through a fiber bushing 38 and are respectively connected to contact springs 39 and 39' with which the bridge member makes direct contact.

The operating lever is provided with a pin or projection 40 which, while passing either switch casing, is adapted to cause oscillation of the switch by contact with one or the other of the depending portions 32, 32', and therefore the operating lever will cause the switch either to make or break the circuit at such point. With reference now to Figs. 2 and 3, it will be observed that when the operating lever is in mid position or at any point between the two switches, both switches will be closed and the lamps burning. In such position the two depending portions 32 of the two switches both extend within the range of the projection or pin 40 on the operating lever. Hence, when the operating lever is moved to start the car, it will have passed on its way a comparatively short distance until the pin 40 strikes one or the other of the depending portions 32 causing the switch on that side to be thrown out of engagement with the contacts 39 and 39', breaking the circuit 17 and extinguishing the light. The other switch, however, remains in closed position. In other words, the arrangement is that at least one of the two switches is always closed. On the return of the operating lever to stopping position, the pin 40 will engage the depending portion 32' of the switch last operated upon thereby, causing the switch to become closed, relighting the lamps. The inside of each switch casing is preferably lined throughout with insulating fiber as shown at 41, and the lid 28' of such casing is secured in place by means of a lip 28" which hooks over a fixed stud 42 at one end, the other end of the lid being secured preferably to the pivot stud 31 by means of a single screw 43. Said lid also is preferably provided with lateral flanges 44 to assist in holding it in place. The construction of the depending portions 32 and 32' of the oscillating switches 30 and their relation to the pin 40 on the operating lever are such that should either of the switches be tampered with maliciously or otherwise, causing it to swing on its pivot to the position opposite from which the controller may have left it, no damage will result. In other words, it will be noted that each of the depending portions is provided with an inclined wall 32^a on the outside or the side remote from the pivot 31, the effect of which is, for instance, if the operating lever should be moved beyond a switch as shown at the right of Fig. 3, and before the operating lever is returned toward stopping position

some one should maliciously or inadvertently strike the lowermost depending portion so as to cause the switch to bridge the contacts and cause the depending portion 32 to be depressed, the operating lever on making its next trip will simply ride against the wall 32^a of the depending portion 32, throwing the switch momentarily out of contact. The operating lever passing, however, in the same direction, will almost immediately thereafter cause the resetting of the switch for operation in accordance with the invention.

Having thus described my invention, I claim as new and desire to secure by Letters Patent:—

1. In a device of the character set forth, an illuminator casing, means to support the casing in upright position, a reflector extending from one end of the casing to the other, an electric circuit, a pair of lamps arranged in said circuit, said lamps being secured in sockets at the opposite ends of the inside of said reflector, and a face plate for the casing serving to concentrate the rays of light from the lamps to cause the same to flash downwardly in front of the casing.

2. In a device of the character set forth, the combination of an illuminator casing for cars, means to support the casing in upright position, a circuit leading through the supporting means, a pair of lamps arranged one above the other in said casing and connected in parallel in said circuit, a key switch within the casing, said casing having means for concentrating all of the rays of light from said lamps and causing the same to flash downwardly across the bottom of the car in front of the casing, and means for automatically making and breaking the circuit through the lamps coincidentally with the stopping and starting of the car.

3. The combination with a car, of a thresh-old illuminator for said car having an electric lamp therein, an electric circuit for said lamp, an operating lever in said car adapted to be moved in back and forth directions, a movable switch for said circuit adapted to be thrown to one position to light said lamp and to another position to extinguish said lamp, said switch being constructed and arranged with respect to the path of movement of said operating lever so that when said operating lever is moved in one direction it will engage said switch and throw the same into its position for lighting the lamp and when moved in the other direction it will engage said switch and throw the same into its position for extinguishing the lamp.

4. The combination with a car, of a thresh-old illuminator for said car having an electric lamp therein, an electric circuit for said lamp, an operating lever in said car adapted to be moved in back and forth directions, a movable switch for said circuit adapted to be

- thrown to one position to light said lamp and to another position to extinguish said lamp, said switch being constructed and arranged with respect to the path of movement of said operating lever so that when said operating lever is moved in one direction it will engage said switch and throw the same into its position for lighting the lamp and when moved in the other direction it will engage said switch and throw the same into its other position for extinguishing the lamp, said switch having means tending to hold it in either of its positions into which it is thus thrown.
5. The combination with a car, of a threshold illuminator for said car having an electric lamp therein, an electric circuit for said lamp, an operating lever in said car adapted to be moved in back and forth directions, 20 a movable switch for said circuit adapted to be thrown to one position to light said lamp and to another position to extinguish said lamp, said switch being constructed and arranged with respect to the path of movement 25 of said operating lever so that when said operating lever is moved in one direction it will engage said switch and throw the same into its position for lighting the lamp and when moved in the other direction it will engage said switch and throw the same into its position for extinguishing the lamp, said switch being provided with means so that in whatever position it may happen to be it will nevertheless be engaged by the lever 30 in its movement theretofore and thrown into a position corresponding to the last direction of movement of said lever.
6. The combination with a car, of a threshold illuminator for said car having an electric lamp therein, an electric circuit for said lamp, an operating lever in said car adapted to be moved in back and forth directions from a central position, movable switches for said circuit one at each side of 40 the central position of said operating lever and each switch adapted to be thrown to one position to light said lamp and to another position to extinguish said lamp, said switch being constructed and arranged with respect to the path of movement of said lever so that when said lever is moved in either direction from its central position it will engage one of said switches and throw the same to a position for extinguishing said lamp and when returned to its central position said lever will engage said switch and throw it into a position for lighting said lamp.
7. The combination with a car, of a threshold illuminator for said car having an electric lamp therein, an electric circuit for said lamp, an operating lever in said car adapted to be moved in back and forth directions from a central position, movable 50 switches for said circuit one at each side

of the central position of said operating lever, each switch adapted to be thrown to one position to light said lamp and to another position to extinguish said lamp, said switches being connected in series in said circuit so that when either of said switches is in its open position said circuit is broken, and being constructed and arranged with respect to the path of movement of said operating lever so that when said lever is moved in either direction from its central position it will engage one of said switches and throw the same to a position for extinguishing said lamp and when returned to its central position said lever will reengage 80 said switch for throwing it into a position for lighting said lamp.

8. The combination with a car, of a threshold illuminator for said car having an electric lamp therein, an electric circuit for said lamp, an operating lever in said car adapted to be moved in back and forth directions, a movable switch for said circuit adapted to be thrown to one position for lighting said lamp and to another position for extinguishing said lamp, said switch having two depending portions one depending portion being always in the path of said operating lever and said lever when moved in one direction being constructed to engage one depending portion of said switch to throw the switch from the position in which it is located and to bring the other depending portion of said switch into the path of said lever ready to be engaged by said lever 100 in its return movement.

9. The combination with a car and an operating lever therefor arranged to be moved to either side of a stopping position in order to start said car, of a threshold illuminator for said car comprising an electric lamp, an electric circuit for said lamp including two switches, one upon each side of the stopping position of said lever in the path of movement thereof, and means whereby the movement of said lever to either of its starting positions effects directly the opening of the corresponding switch and whereby the return of said lever toward stopping position effects directly the closing of 115 said switch.

10. The combination with a car and an operating lever therefor arranged to be moved to either side of a stopping position in order to actuate said car, of a threshold illuminator for said car comprising an electric lamp, a single electric circuit for said lamp having therein two switches, one upon each side of the stopping position of said lever in the path of movement thereof, each of said switches being constructed to remain in open position or in closed position, as left, and being arranged to be engaged by said lever and moved to open position as said lever moves toward actuating position and 125 139

to be engaged again and moved into closed position as said lever moves toward its stopping position.

11. The combination with a car and an operating lever therefor arranged to be moved to either side of a stopping position in order to start said car, of a threshold illuminator comprising an electric lamp, a normally closed circuit for said lamp including two switches, one upon each side of the stopping position of said lever, and means directly connected to the respective switches and extending into the path of movement of said lever to be engaged by said lever as it moves to either of its starting positions to effect directly the opening of the corresponding switch and to be engaged again by said lever as it returns toward the stopping position to effect directly the closing of said switch. 70

12. The combination with a car and an operating lever therefor arranged to be moved to either side of a stopping position in order to actuate said car, of a threshold illuminator comprising an electric lamp, a normally closed circuit for said lamp including two switches, one upon each side of the stopping position of said lever and constructed to remain in open position or in closed position, as left, and means whereby the movement of said lever past either of said switches toward either actuating position of said lever effects directly the opening of said switch and whereby the return of said lever toward its stopping position effects the closing of said switch. 80

13. The combination with a car and an operating lever therefor arranged to be moved to either side of a stopping position in order to start said car, of a threshold illuminator comprising an electric lamp, a normally closed electric circuit for said lamp including two switches, one upon each side of the stopping position of said lever in the path of movement thereof, and coöperating engaging members upon said lever and said switches constructed and arranged so that said lever by its movement to either of its starting positions effects directly the opening of the corresponding switch, and by its return movement toward stopping position effects directly the closing of said switch. 90

14. The combination with a car, of a threshold illuminator for said car having an electric lamp therein, an electric circuit for said lamp, an operating lever in said car adapted to be moved in back and forth directions, a movable switch for said circuit adapted to be thrown to one position for lighting said lamp and to another position for extinguishing said lamp, said switch having two depending portions one depending portion being always in the path of said operating lever and said lever when moved in one

direction adapted to engage one depending portion of said switch to throw the switch from the position in which it is located and to bring the other depending portion of said switch into the path of said lever ready to be engaged by said lever in its return movement, and means to insure that said lever in its return movement will be able to engage the other depending portion of said switch and thus throw it into an opposite position from that in which it was placed by the first movement of said lever. 75

15. The combination with a car, of a threshold illuminator for said car having an electric lamp therein, an electric circuit for said lamp, an operating lever in said car adapted to be moved in back and forth directions, a movable switch for said circuit adapted to be thrown to one position for lighting said lamp and to another position 85 for extinguishing said lamp, said switch having two depending portions one depending portion being always in the path of said operating lever and said lever when moved in one direction adapted to engage one depending portion of said switch to throw the switch from the position in which it is located and to bring the other depending portion of said switch into the path of said lever ready to be engaged by said lever in its return movement, and means comprising an inclined outer wall on each of said depending portions for engagement by said operating lever to insure that said lever in its return movement will be able to engage the other depending portion of 90 said switch and throw it into an opposite position from that in which it was placed by the first movement of said lever. 95

16. The combination with a car, of a threshold illuminator for said car having an electric lamp therein, an electric circuit for said lamp, an operating lever in said car adapted to be moved in back and forth directions, a movable switch for said circuit 105 adapted to be thrown to one position for lighting said lamp and to another position for extinguishing said lamp, said switch comprising a pivoted arm forked at its lower end to form two separated depending 110 portions, circuit contacts adapted to be closed by the upper portion of said switch arm, each of said depending portions having inclined side walls converging to a narrow edge, a pin on said operating lever 115 adapted to engage an inclined side wall on one of said depending portions and throw said switch from one of its positions to the other when said operating lever is moved past said switch, said pivoted switch arm at all 120 times having one or the other of its depending portions in the path of said operating lever with an inclined side wall ready to be engaged by the pin on said operating lever. 125

17. The combination with a car, of a 130

threshold illuminator comprising a vertically arranged casing having an elongated vertical opening facing across the threshold of said car; a plurality of lamps one above the other in said casing to throw light out from said elongated opening, and a series of downwardly inclined spaced and overlapping shutters fixedly mounted in front of said opening so as to throw the rays of light from said lamps in a downwardly inclined direction across said threshold.

18. The combination with a car, of a threshold illuminator comprising a vertically arranged casing having an elongated vertical opening facing across the threshold of said car, a plurality of lamps one above the other in said casing to throw light out from said elongated opening, an electric circuit for said lamps, means for automatically making and breaking the circuit through said lamp coincidently with the stopping and starting of the car, and a series of downwardly inclined spaced and overlapping shutters fixedly mounted in front of said opening so as to throw the rays of light from

said lamps in a downwardly inclined direction across said threshold.

19. The combination with a car, of a threshold illuminator comprising a vertically arranged casing having an elongated vertical opening facing across the threshold of said car, a plurality of lamps one above the other in said casing to throw light out from said elongated opening, an electric circuit for said lamps, means for automatically making and breaking the circuit through said lamp coincidently with the stopping and starting of the car, and a hand-operated switch mounted within said casing for controlling said electric circuit, and an openable cover in said casing for normally protecting said switch.

In testimony whereof I have signed my name to this specification in the presence of two subscribing witnesses.

CHARLES E. MOORE.
